UNITED STATES PATENT OFFICE.

JAMES H. BAKER, OF CHICAGO, ILLINOIS.

MECHANISM FOR CONVERTING MOTION.

SPECIFICATION forming part of Letters Patent No. 691,697, dated January 21, 1902.

Application filed August 15, 1900. Renewed April 4, 1901. Serial No. 54,319. (No model.)

To all whom it may concern:

Be it known that I, JAMES H. BAKER, a citizen of the United States, residing at Chicago, Cook county, State of Illinois, have invented 5 certain new and useful Improvements in Mechanism for Converting Motion, which are fully set forth in the following specification, reference being had to the accompanying drawings, forming a part thereof.

10 In the drawings, Figure 1 is a side elevation of my device. Fig. 2 is a section at the line 2 2 on Fig. 1. Fig. 3 is a section through one of the clutches at the line 3 3 on Fig. 2.

The purpose of this invention is to provide 15 an improved means for converting an oscillating or reciprocating movement into a rotary movement in such manner that every unit of movement of an oscillating or reciprocating element pertaining to the device shall 20 yield substantially the same rotary movement and that the change of direction of oscillation or reciprocation may occur without any tendency to arrest or retard the rotary movement, so that when the reciprocation or 25 oscillation is produced by the hand or foot of an operator no loss or absorption of power may be caused by unskillfulness on the part of the operator in keeping time with the rotary movement.

30 A represents the shaft of any mechanism to be operated to which my device may be applied; B, a fly-wheel on such shaft. C and C' are clutch-disks rigid with the shaft, each constituting one element of a clutch pair, of 35 which the other elements are gear-wheels D D', respectively, said gear-wheels being journaled on the shaft A and cut away at the center, so that a peripheral portion d, comprising the gear-rim, encompasses a reduced portion 40 c of the clutch-disk C. Into said encompassing portion I preferably set rigidly a steel plate E, having oblique pockets E' E' for the clutch-rolls F F', which operate in a well-understood manner to cause the gear-rim or 45 outer element of the clutch to rotate the inner element in one direction and to ride idly thereon in the reverse direction. The pockets for the clutch-rolls are located so that at any 50 position in the range of oscillation of the outer element at least one of the rolls is by gravity lodged on the shoulder c in position to per-

form its clutching function upon proper movement of the outer element. Both the clutches are arranged to drive the gears or be driven by them in the same direction of rotation. 55

At two points in a line intersecting the axis of the shaft A and both at the same side of said axis there are fulcrumed levers G and G', the former, which is nearer to the shaft A, having an internal segment-rack g, which 60 meshes with the gear D on the side opposite that at which the fulcrum of the lever G is located, while the latter, having its fulcrum more remote from the shaft A, has an exterior segment-gear g' meshing with the gear D' on 65 the side toward the fulcrum of said lever. One of said levers has arms G² G², by which it may be operated either directly by the hand of the operator or by means of a pitman H, connected with a pedal. (Not represented.) The other 70 lever has an arm G³, which extends alongside one of the arms G² of the first lever and has a stud G³⁰, preferably provided with an anti-friction-roll, protruding into a slot G²⁰ in the arm G², so that the oscillation of the first lever 75 communicates oscillatory motion to the second lever, the slotted connection between the two having the purpose and effect of accommodating the movement of the two levers 80 to each other in view of the distance between 85 their fulcrums. The range of oscillation of the operating-lever G² comprises an angle so situated with relation to the plane containing the pivot-axes of the two levers and the slot G²⁰ extends in such direction relative to the 90 pivot-axis of the lever G² that said operating-lever G² communicates to the second lever an angular movement equal to its own, and the pitch radii of the two segment-racks being 95 equal and the gear-wheels with which they respectively mesh being of equal diameter said gear-wheels receive equal rotative movement from each oscillation of the oscillating lever, but in opposite directions. Thus at each oscillation one of the gears receives movement in the direction causing it by its clutch to drive the shaft A, while the other from the same movement is rotated in reverse direction about the shaft, as permitted by the structure of the clutch, without driving or resisting the driving of the shaft. In the opposite 100 oscillation the situation is reversed and the

second gear becomes the driving-gear, while the first gear is rotated in reverse direction about the shaft. The rotation of the shaft is thus continuous and independent even of the 5 length of oscillation of the lever at each stroke, the momentum of the fly-wheel or mechanism tending to continue the rotation communicated by any stroke, however short, of the lever during any interval which may intervene 10 between the oscillation of the lever in the opposite directions.

In order to give to the operating-lever G^3 a tendency to return from the extreme of its movement in either direction, I connect with 15 it by means of the yoke G^4 , which is wide enough to span all the pivotal connections, a rigid stem G^{10} , which extends in a direction at right angles to the extent of the lever-arm G^2 , and on said stem I secure a weight K , 20 which operates as a pendulum-ball, tending to rest at the lowest position and to hold the lever-arm G^2 substantially horizontal when it comes to rest in such lowest position. Being disturbed from this position by any movement 25 of the lever-arms away from a horizontal position in either direction it tends to cause them to return, and thus causes the whole lever to oscillate back and forth until it settles at the intermediate position, with 30 the lever horizontal and the weight at the lowest point. When the weight is adjusted on the stem at a distance tending to cause the period of oscillation of the entire lever thus weighted to agree with the rate of oscillation 35 suitable to give the desired speed to the mechanism, the operator, conforming to that speed and accommodating his stroke substantially to the natural swing of a pendulum of that length, finds the lever operating substantially 40 as if it were connected by a pitman with a fly-wheel—that is, tending to return at the limit of each stroke, and by its initial movement of return giving the suggestion to the operator to reverse his stroke, thus making the operation much more easy and natural than it 45 would be in the absence of any device tending to give such suggestion.

I claim—

1. A mechanism for converting motion, comprising two gear-wheels, a shaft and two clutches thereon, of which one member of each is rigid with the shaft and the other member is free to revolve about the shaft and is rigid with one of the gear-wheels; two levers, having 55 their fulcrums both at the same side of the axis of the shaft and at different distances therefrom, the lever having the nearer fulcrum having rigid with it an internal gear-segment meshing with one of the gear-wheels, 60 and the lever having the more remote fulcrum having rigid with it an external gear-segment meshing with the other gear; and connections between the two levers by which the oscillation of one about its fulcrum 65 communicates oscillation to the other in the same direction, about its fulcrum.

2. In a mechanism for converting motion, in combination with the two clutches—their respective gears—connected levers having gear-segments operating said gears respectively; one of said levers having a weight which causes its center of gravity to be below the fulcrum, whereby it tends to return the levers to the middle point of their respective paths of oscillation. 70

3. In a mechanism for converting motion, in combination with the two clutches—their respective gears—connected levers having gear-segments operating said gears respectively; one of said levers having a weight 80 which causes its center of gravity to be below the fulcrum, whereby it tends to return the levers to the middle point of their respective paths of oscillation; said weight being adjustable vertically on the lever to adapt the 85 natural time of oscillation of the lever as a pendulum to the speed which it is desired to have the lever communicate to the gears.

4. A mechanism for converting motion, comprising two wheels, a shaft and two clutches 90 thereon, of which one member of each is rigid with the shaft and the other member is free to revolve about the shaft and is rigid with one of the wheels; two segments fulcrumed at different points but at their respective 95 centers, and means whereby they act upon the wheels respectively to rotate the same; and connections between such segments to cause either one to actuate the other in direction to give reverse movement to their respective wheels. 100

5. A mechanism for converting motion, comprising two wheels; a shaft and two clutches thereon, of which one member of each is rigid with the shaft and the other member is free 105 to revolve about the shaft and is rigid with one of the wheels; two segments fulcrumed at different points at their respective centers, acting upon the wheels respectively at opposite sides of the shaft to rotate said wheels; 110 and connections between said segments to cause either one to actuate the other to give reverse rotary movement to their respective wheels. 115

6. A mechanism for converting motion, comprising two wheels; a shaft and two clutches thereon, of which one member of each is rigid with the shaft and the other member is free to revolve about the shaft and is rigid with one of the wheels; two segments of equal 120 radius, fulcrumed at different points at their respective centers, and acting upon the wheels respectively to rotate the same, and connections between such segments to cause either one to actuate the other in direction to give 125 reverse movement to their respective wheels.

7. A mechanism for converting motion, comprising two wheels; a shaft and two clutches thereon, of which one member of each is rigid with the shaft and the other member is free 130 to revolve about the shaft and is rigid with one of the wheels; two segments of equal

radius, fulcrumed at different points but at their respective centers and acting on the wheels respectively at opposite sides of the shaft, and connections between such segments to cause either one to actuate the other in direction to give reverse rotary movement to their respective wheels.

In testimony whereof I have hereunto set

my hand, at Chicago, Illinois, in the presence of two witnesses, this 7th day of August, A. D. 1900.

JAMES H. BAKER.
